UNITED STATES PATENT OFFICE

2,631,743

PARKING GARAGE

Hugo Hornick, Chicago, Ill.

Application May 24, 1950, Serial No. 163,886

1. Claim. (Cl. 214—16.1)

1

My invention relates to a parking garage in which all movement is unobstructed by traffic in cross or opposite directions so as to insure prompt entrance, parking and exit.

Among the objects of my invention is to provide a parking garage built in the form of a spiral ramp with an inner driveway leading from the entrance to the parking spaces, a central portion divided up into crosswise parking spaces, and an outer driveway leading from the parking spaces to the exit.

Another object is to provide the entrance portion of the spiral ramp with stops for halting a car at the first available parking space, and turntables for moving the car into the central parking space.

Another object is to provide a parking garage with maximum speed in entrance, parking and exit with a minimum staff required for operation.

My invention also contemplates such other objects, advantages and capabilities which will later more fully appear, and which are inherently possessed by my invention.

While I have shown in the accompanying drawings preferred embodiments of my invention, yet it is to be understood that the same are susceptible of modification and change without departing from the spirit of my invention.

Referring more particularly to the drawings, Fig. 1 is an elevational view partially broken away to show the entrance and exit; Fig. 2 is a broken plan view of the same in smaller scale; Fig. 3 is a plan view of the ramp; Fig. 4 is a top plan view of another embodiment broken away to show the exit; Fig. 5 is a top plan view of the turntable; Fig. 6 is a sectional view showing the parking arrangement; and Fig. 7 is a detailed sectional view of the turntable.

Referring more now to my invention, I provided a spiral ramp 10 supported by a plurality of spaced round pillars 11. The ramp and the pillars are preferably formed of cement. The spiral ramp is divided transversely into three portions. The inner portion 12 leads from the entrance 13 and is the driveway on which the cars enter for parking. The adjacent portion of the ramp is the parking area 14 divided up into a plurality of parking spaces. On the other side of the parking area 14 is the outer driveway 15 on which cars leave the parking spaces and move out the exit 16.

Such arrangement permits the driver to drive in, park his own car and when ready, drive out. The driver meets no cross traffic nor any on-coming traffic. He drives in, makes a quarter

turn to the right to park. When he is ready to leave, he makes another quarter turn to the right and drives down the ramp and out the exit. Only a minimum of help is necessary with a serviceman at the entrance and another at the exit being all that is needed.

A plurality of self-operated electrically driven elevators 17 are spaced so that one of the elevators is near each parking space. When the 10 driver has parked his car, he may descend by the nearest elevator. When the driver returns, he may use the same elevator to reach the level on which his car is parked.

In another embodiment of my invention, I 15 provide driveway 12 with a turntable 18 opposite each parking space in area 14. At the forward position of each turntable 18 are a pair of stop pins 19. When a parking space in area 14 is not occupied, the turntable 18 adjoining 20 this unoccupied space has its approaches ready to receive the wheels of a car, and stop pins 19 extend above the floor of driveway 12. The driver drives his car until its front wheels contact stop pins 19. This sets up an electrical 25 contact which operates turntable 18 and moves it and the car on it a quarter turn to the right and stops. The driver then drives the car into the parking space in area 14 and leaves the car until he returns to it. The driver then makes 30 a right quarter turn and moves down outer portion 15 of ramp 10 out exit 16.

When turntable 18 turns upon contact of the 35 wheels against stop pins 19, the stop pins move downwardly in holes 20 in the floor of turntable 18 until they are substantially even with the floor of the turntable. This permits the parked car to drive past this point to the exit driveway 15. When a driver drives his car out of the parking space, an electrical contact 40 switch in the parking space operates to turn the turntable 18 a quarter turn to the left back to its first position. At the same time, the electrical contact raises the stop pins 19 to upright position.

45 It is within the contemplation of my invention that turntable 18 and stop pins 19 may be manually operable, but I prefer to have them operate electrically.

In operation of my parking garage, a driver 50 on entering at the entrance, receives a parking ticket from an attendant. This attendant consults a light signal information board which indicates spaces occupied and unoccupied, and tells the driver where the first unoccupied space 55 is located. The driver drives on to the space

which is identified by a green light overhead in the ceiling. The driver then proceeds until his front wheels contact the stop pins, as heretofore described.

In the event that my spiral ramp exceeds four circles in height, I provide an entrance elevator and an exit elevator for the cars for every four circles. The entrance elevator 21 is built at the inner part of the garage to communicate with the fifth circle of driveway 12, and the exit elevator 22 is built at the outer part of the garage to communicate with the fifth circle of outer driveway 15.

When a car is leaving, it stops at the exit and the attendant there takes up the ticket, figures out the time charge and receives payment from the driver.

The empty center space may be utilized for a warehouse with a central freight elevator and an adjacent entrance on one side and an exit on the other side.

While my spiral ramp is formed preferably in circular form, yet it may be oval or even angular and still be within the spirit of my invention.

Having thus described my invention, I claim:

A spiral parking garage having an entrance and an exit and comprising a plurality of spaced supports, a single wide spiral ramp mounted on said supports, said ramp having an inner entrance driveway communicating with the entrance to the garage, and an outer exit driveway communicating with the exit to the garage, and a parking area between said inner entrance driveway and said outer exit driveway, said parking area divided into a plurality of parking spaces transverse to said driveways, a plurality of turntables positioned on and extending down within said inner entrance driveway, said turntables spaced so that a turntable is positioned adjacent each parking space, a motor and an electrical circuit connected to an

electrical power source and attached to said turntables, a pair of stop pins movably mounted in each of said turntables, said stop pins adapted to be in upright position when the adjacent parking space is not occupied by a car, said upright stop pins upon being contacted by the front wheels of a car driven on the turntable on the inner entrance driveway adapted to close said electrical circuit to move the turntable a quarter turn to the right so that the car thereon faces the adjacent parking space, said stop pins just contacted adapted to drop within openings in the inner entrance driveway to substantially level with the inner entrance driveway to permit the car to pass therebeyond to the adjacent parking space, said adjacent parking space adapted to receive the car driven thereon, and said outer exit driveway adapted to receive cars turned substantially at right angles thereon from said parking spaces and to permit said cars to be driven spirally downwardly thereon to the exit of the garage, and electrically operated contacts positioned in each of said parking spaces and adapted upon a car leaving the parking space to close the electrical circuit to turn the adjacent turntable a quarter turn to the left and move its stop pins to upright position.

HUGO HORNICK.
